UNITED STATES PATENT OFFICE

ANTONIO LONGORIA, OF LAKEWOOD, OHIO

DESIGN FOR A CASING FOR AN AIR PURIFIER

Application filed January 26, 1929. Serial No. 29,790. Term of patent 7 years.

To all whom it may concern:

Be it known that I, ANTONIO LONGORIA, a citizen of the United States, residing at Lakewood, in the county of Cuyahoga and State of Ohio, have invented a new, original, and ornamental Design for a Casing for an Air Purifier, of which the following is a specification, reference being had to the accompanying drawing, forming part thereof:

In said drawing, Fig. 1 is a front elevation

of said casing for an air purifier, showing my new design; Fig. 2 is a side elevation thereof; Fig. 3 is a top plan view thereof; Fig. 4 is a rear elevation thereof; and Fig. 5 is a bottom plan view thereof.

I claim:

The ornamental design for a casing of an air purifier, as shown.

ANTONIO LONGORIA.
